HOOD FOR A POWER MEAT CUTTER

Edward C. Karp, Belvidere, Ill., assignor to Sanitary Scale Company, Belvidere, Ill., a corporation of Illinois

Application February 8, 1955, Serial No. 34,412

Term of patent 14 years

(Cl. D55—1)

Fig. 1.

Fig. 2.

Fig. 3.

I claim:

The ornamental design for a hood for a power meat cutter, substantially as shown.
